CLAIM

The ornamental design for a molding machine part, as shown and described.

DESCRIPTION

FIG. 1 is a front perspective view of the claimed design for a molding machine part;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof; and,

FIG. 8 is a back perspective view thereof.

The broken lines immediately adjacent to the shaded area depict boundaries of the claimed design and form no part thereof. The broken lines showing the remainder of the molding machine part depict environmental structure and form no part of the claimed design. Portions of the molding machine part not shown in the drawing form no part of the claimed design.
